Patented Oct. 31, 1911.

UNITED STATES PATENT OFFICE.

WILLIAM H. GOODIN, OF RENO, NEVADA.

ADDING AND REGISTERING DEVICE.

1,007,350.

Specification of Letters Patent. Patented Oct. 31, 1911.

Application filed January 17, 1911. Serial No. 603,047.

To all whom it may concern:

Be it known that I, WILLIAM H. GOODIN, citizen of the United States, residing at Reno, in the county of Washoe and State 5 of Nevada, have invented new and useful Improvements in Adding and Registering Devices, of which the following is a specification.

This invention relates to a counting device, and particularly to an automatic 10 checking counter.

The object of this invention is to provide a simple tool whereby an operator can mark and simultaneously register the number of 15 articles marked.

This invention consists of the parts and the combination and construction of parts hereinafter more fully described and claimed having reference to the accompanying 20 drawings, in which—

Figure 1 is a side elevation of the marking counter. Fig. 2 is a vertical longitudinal section through the device. Fig. 3 is a transverse section showing the locking 25 band in the locked position.

It is desirable to provide a tool or device whereby salesmen or other persons having occasion to check off or mark stock, as for instance when an inventory is being taken, 30 may also simultaneously keep an accurate count of the number of articles checked or marked. To this end I provide in combination a suitable marking implement, as a pencil, crayon or equivalent device, 2, 35 adapted to be clamped in a clutch or grip 3, formed upon a sleeve 4, reciprocably mounted in a handle or casing 5. At the opposite end of the casing 5 from that in which the pencil is mounted is attached a suitable 40 counting device, designated generally as at 6, the mechanism of which is adapted to be actuated by the compression of the sleeve 4 within the casing 5. A spring 7 is re-active 45 between the inner end of the pencil carrier 4 and a fixed abutment member 8 to normally thrust the pencil outwardly until the movement of the sleeve 4 is further prevented by means of a screw, or other suitable device 9, movable in a slot 10 formed 50 in the casing 5.

Manifestly any appropriate form of counter as 6, may be utilized in carrying out my invention, and I do not wish to be understood as limiting myself to any specially 55 constructed counter mechanism.

The counting mechanism comprises a se-

ries of indexed rings 12 revolvably mounted in a chambered cap 13 from which projects a stem 14 on which is mounted a unit ring 12, turnable thereby. Motion is transmitted 60 from the unit ring 12 through the remaining rings by pinions 15 loosely mounted on the cap 13 and engaging respective projections 16—17 on adjacent pairs of rings 12. The stem 14 is automatically turned by a 65 ratchet clutch 18 carried thereon and driven by a complementary member 19 secured on a spiral spindle 20 reciprocable in a nut 21 fixed in the sleeve 4.

In operation, when the sleeve 4 is pushed 70 up, by the application of the pencil 2 to a substance, the nut 21 turns the spindle 20 and its clutch member 19, this in turn revolving the member 18 and its associated counting train. When the sleeve 4 moves 75 down under action of spring 7 the clutch members ratchet freely without revolving the stem 14 by which the rings 12 may be reset when desired.

Any appropriate locking device may be 80 employed to prevent the movement of the sleeve 4 when it is desired to use the implement only for marking and as here shown the lock comprises a spring band 22 circumferentially movable over the slot 10 when 85 the screw 9 moves down, and when so moved, one of the ends, as 23, of the band, may spring into the slot to temporarily retain the band in this position. When the instrument is to be used as a counter also, 90 then the band 22 is revolved until a transverse projection 24 forming a passage way for the screw 9 is over the latter, thus permitting this to pass beneath the band when 95 the sleeve moves.

Having thus described my invention what I claim and desire to secure by Letters Patent is—

1. An adding and registering device including a register, a cylindrical casing in which the register is fixed, a point or pencil-holding member slidably guided within the casing and having a spiral nut in the upper end, a ratchet, one member of which is turnably connected with the register, a spiral 100 pin connected to the other ratchet member and slidably through the nut, a spring by which the point-carrying member is normally extended, and a band turnable about the casing and engageable with the point 105 carrier to lock said point carrier.
2. An adding and registering device in-

cluding a register, a cylindrical casing in which the register is mounted, having a longitudinal slot, a pencil-holding member slidably guided within the casing and having connections for actuating the register by its longitudinal movement in the casing, and provided with a guide pin extending exteriorly through the casing slot, and a band turnable about the casing and having 10 a portion thereof pressed inwardly to ex-

tend into the casing slot and a portion pressed outwardly to permit movement of the said guide pin, for the purpose specified.

In testimony whereof I have hereunto set my hand in the presence of two subscribing 15 witnesses.

WILLIAM H. GOODIN.
